UNITED STATES PATENT OFFICE.

LEE G. DANIELS, OF ROCKFORD, ILLINOIS.

WATER-SOFTENER VALVE MECHANISM.

Application filed April 21, 1927. Serial No. 185,509.

This invention relates to water softeners of the base exchange type and is devoted more particularly to improvements in the valve mechanism for hand operated softeners such as are more extensively provided for domestic use.

The principal object is to provide a simplified and inexpensive type of valve mechanism and one which makes it easy for the average person to put the softener through its regenerations.

Hand operated softeners have heretofore required a number of valves which had to be opened and closed separately in a certain prescribed order to properly control the flow of water in softening and regeneration. This made it very confusing for the average mechanically unskilled person to regenerate the softener, and it was only by dint of the use of an instruction book kept at hand for reference on each occasion of regeneration that the average user could operate the softener without confusion and mistakes. The present invention is therefore principally directed toward avoiding this objectionable feature by providing a valve mechanism operated by a single hand lever shiftable to different positions according to a predetermined scheme, the different positions being clearly indicated on a face plate with reference to which the lever is moved so that the operator is insured against the likelihood of doing anything out of turn and reduces the regeneration of the softener to a matter of routine.

According to the present invention a hand lever is provided swingable from one limit position to another in a guide slot provided in a face plate, the lever in its different positions being arranged to operate the valve mechanism differently to secure the proper connections for the softener for softening, regeneration, etc., and the face plate being provided with markings to indicate the different positions for the lever and having means for holding the lever selectively in any desired position. The different positions are suitably numbered in the order in which the lever should be moved thereto so that guess-work is entirely eliminated and nothing is left to the special judgment of the operator.

Another important feature of the invention consists in the provision of means whereby the extent of valve opening in softening

and regeneration may be varied to secure a predetermined rate of flow of water regardless of the available water pressure in the particular locality where the softener is installed. In the present embodiment where the means for holding the hand lever in its different positions has a fixed location the fulcrum for the lever is adjustable so that the lever in its different positions will open the valves more or less, depending on the degree of adjustment of the fulcrum.

The invention is illustrated in the accompanying drawings wherein Fig. 1 is a front view of a softener equipped with my improved valve mechanism; Fig. 2 is a front view of the valve mechanism itself on an enlarged scale, and Figs. 3 and 4 are side views showing the hand lever in different positions, that shown in Fig. 3 being the #3 position designated "Wash" on the face plate (meaning the salt wash or regeneration flow), while that shown in full lines in Fig. 4 is the #4 position for softening operation designated "Soft" on the face plate and that shown in dotted lines in the same figure is the #1 position designated "Salt" on the face plate for the water draining and salt charging operation. The same reference numerals are applied to corresponding parts throughout the views.

The softener comprises a tank 10 serving as a container for a bed of zeolite mineral or other water softening material. Hard water is supplied to the softener from any suitable source, as, for example, the city water mains, through a pipe 11 and soft water is arranged to be discharged to the service system through a pipe 12. A pipe 13 connects at 14 with the lower end of the tank preferably through a distributor pipe or other means for distributing the water flow, while another pipe 15 connects with the upper end of the tank as at 16. The service pipe 12 and the pipe 15 are both in open connection with the upper end of the tank at all times. The hard water supply pipe 11, however, is arranged to be placed selectively in communication with either end of the tank through the valve mechanism indicated generally by the reference numeral 17, the valve mechanism being also arranged to shut off either communication as will hereinafter appear. In the normal softening operation the hard water supplied through the pipe 11 flows through communi-

cating passages in the valve mechanism 17 and passes downwardly through the pipe 13 as indicated by the full line arrow for passage into the lower end of the tank beneath the bed of water softening material therein. The distributing means in the bottom of the tank, as previously mentioned, distributes the water evenly throughout the cross-sectional area of the bed for uniform contact with the material, and the water in passing upwardly through the bed is softened and is supplied to the service system through the pipe 12. When the softener is to be regenerated, salt or brine is arranged to be injected into a head space in the tank above the material therein through the neck 18. The latter has a cap 19 suitably clamped in place by the hand screw device 20. During regeneration the hard water supplied through the pipe 11 is conducted through registering passages in the valve mechanism 17 upwardly through the pipe 15, as indicated by the dotted arrow, for discharge into the upper end of the tank. This water picks up and dissolves or assimilates the salt or brine for passage downwardly through the mineral for the purpose of causing a chemical exchange, commonly termed "base-exchange", to occur between the brine and the mineral to revive or regenerate the exhausted mineral. The waste water leaving the lower end of the tank passes upwardly through the pipe 13 as indicated by the dotted arrow and is conducted to the sewer through a waste pipe 21. Broadly speaking, no invention is claimed in the mere provision of means for introducing hard water at one end of the tank and discharging soft water at the other end, or in means for controlling the direction of water flow so as to carry brine or dissolved salt through the mineral in the reverse direction from the softening flow and discharging the waste water to the sewer. Such means, generally speaking, are well known in this art. However, as will hereinafter appear, I have provided improved means whereby practically anyone relatively unskilled in a mechanical way may put the softener through these operations with much greater ease and facility, and invention is therefore claimed in this case in the valve mechanism and its novel control means.

The present valve mechanism constitutes a considerable improvement over those provided in the past with which I am familiar by reason of the fact that I have enabled the use of spring closed valves in place of rotary plug cock valves which proved more or less unsatisfactory because they necessitated special lubrication to avoid sticking and were furthermore apt to show leakage after being in service for a time. Thus three valves 22, 23 and 24 of the quick open-

ing and self closing type, commonly known as "whistle" valves, are employed, the valve 22 controlling communication between the pipe 11 and the pipe 15, the valve 23 controlling communication between the pipe 11 and the pipe 13, and the valve 24 controlling communication between the pipe 13 and the waste or drain pipe 21. The pipe 11 is connected between the valves 22 and 23 as fully appears while the valve 24 is connected with the pipe 13 below the valve 23 by means of the pipe 25. The three valves are controlled by a single hand lever 26 movable from one limit position to another in a slot 27 relative to a face plate 28 bearing suitable markings, as indicated at 29, to aid the operator in shifting the lever in the control of the softener. Thus the position marked "1-salt" indicates the place to which the lever must be moved when the softener is to be charged with salt or brine at the commencement of the regenerating operation. At this point the operator removes the cap 19, pours in the proper amount of salt or brine, and then replaces the cap. The position marked "2-off" indicates the place to which the lever must be moved in order to completely shut off the softener to allow the mineral to stand for a time to "soak" in order that the mineral will have an opportunity more thoroughly to make a chemical exchange with the brine. It is usually desirable to keep the lever at this position for about thirty minutes before commencing the salt wash and, as a matter of fact, this method of regenerating the softener results in saving in the amount of salt or brine used. The position marked "3-wash" corresponds to the regenerating operation in which the salt or brine is washed through the mineral bed at a predetermined rate, the waste water being discharged to the sewer. At the end of the regeneration the lever is shifted back to the position marked "4-soft" from which position it was moved at the commencement of the series of shifts just described. In this position the softener is in its normal softening operation. Just after regeneration it is usually a good practice to open a bib near the softener, as for example in a laundry tub, long enough to allow all of the hard water in the head space in the tank to be flushed out so that this water will not get into the service system.

The lever 26 is pivoted at 30 on a stud 31 threading into the bracket 32. The latter is fixed as by means of nuts 33 onto the bodies of the valves 22 and 23 and has arms 34 whereon to support the face plate 28, the latter being fastened to the arms by means of screws 35. When the lever 26 is swung to one limit position it depresses the plunger 36 of the valve 22 as indicated in Fig. 3, and when swung to the other limit position

depresses the plunger 37 of the valve 23. The two valves are, of course, of identical construction, and the showing of the one valve in section in Fig. 4 will suffice to convey an understanding of both. The valves are quick opening under the pressure of the lever 26 on the plungers thereof and are self-closing under the action of springs such as that shown at 38. The fact that the valves are held open by the lever against spring action necessitates holding the lever in position to keep the valve open. For this purpose the face plate 28 is provided with pairs of lugs 39 at each of the four lever positions previously described, and a pin 40 is arranged to be entered through openings 41 in the lugs 39 to extend across the slot 27 over the lever 26 and thereby hold the same in position against the action of the valve spring. The pin 40 may be fastened to one end of a cord or chain 42, the other end of which is fastened to the face plate or bracket so as to insure against loss thereof, the cord being of sufficient length to allow the pin to be entered through any one of the pairs of lugs 39 to hold the lever in any one of its positions. Thus the operator at the time of regeneration removes the pin from the #4 position to enable movement of the lever to the #1 position. During the salt charging and water draining operation, the pin is inserted in the lugs 39 behind the lever to hold it in place. After the salt charging operation the pin is again removed and the lever is moved to the #2 position and the pin is replaced behind the same to hold it in its new position. After the soaking, the pin is removed and the lever is swung to the #3 position for the salt wash, the pin being again inserted behind the lever to hold it in place. And finally after the regeneration, the lever is moved back to the #4 position and again locked by the pin 40 to keep it in position throughout the capacity run.

The valve 24 is fastened by means of a nut 43 onto a lateral extension 44 of the bracket 32 and has the spring pressed plunger 45 thereof arranged for operation by a lever 46 pivoted at 47 to the extension 44 of the bracket 32. The lever 46 extends across the path of movement of the lever 26 beneath the slot 27 in the face plate 28 so that the same is engaged and depressed by the lever when the lever is moved to the #1 position. This is shown in dotted lines in Fig. 4 and it will be observed in that figure that the plunger 36 of the valve 22 is not engaged by the lever 26 in such position of the lever. The valve 24, as a matter of fact, is opened only part way with the lever 26 in the #1 position, and it is only when the lever is moved to the #3 position depicted in Fig. 3 that the valve 24 is fully opened along with the valve 22. The reason for restricting the opening of the valve 24 in the #1 position

of the lever is that the opening of the valve is only for the purpose of allowing a certain small amount of drainage of the tank so that there will be sufficient head room in the tank for the charging of salt or brine without causing an overflow. However, when the lever is moved to the #3 position for the salt wash, it is necessary to have the valve 24 opened wider.

Having in mind the considerable variation in water pressures in different communities, I have provided means whereby the extent of valve opening may be varied to secure the proper rate of flow in softening and regeneration regardless of the available water pressure. For this reason the stud 31 may be adjusted by threading in or out in the bracket 32 so as to adjust the fulcrum point 30 with reference to the face plate 28 and thereby adjust the extent of valve opening when the lever is held in the different positions described. The stud 31 may be screwed in or out with reference to the bracket 32 by turning the lever 26 when the same is moved approximately to a position at right angles to the bracket. A lock nut 48 serves to hold the stud 31 in its adjusted position and is tightened when a predetermined rate of flow of water is secured in the softening and regenerating operations. It is, of course, necessary to confine the flow during softening to a rate at which the water will be properly softened. In so far as regeneration is concerned, it is necessary to confine the flow of the water and brine through the mineral bed to a rate at which a complete chemical exchange can properly occur between the brine and the mineral. It will be apparent that the present invention provides for securing the proper rate of flow regardless of the available water pressure.

It is believed the foregoing description conveys a clear understanding of my invention and all of its objects and advantages. It should be apparent that the invention is capable of a certain amount of modification from the particular embodiment herein shown and described and for that reason the appended claims have been drawn with a view to covering all legitimate modifications, adaptations and variations of the invention which may suggest themselves to one skilled in the art as a result of the present disclosure.

I claim:

1. In a water softener, the combination with a softener tank containing softening material, and means for supplying hard water to said tank and withdrawing soft water therefrom, of a plurality of valves for controlling the communication between the softener tank and the source of hard water supply for softening and regeneration and to establish communication between the tank

- and a drain outlet during regeneration, a single lever for operating all of said valves, said lever being movable selectively to any valve and when moved to such position being arranged to operate the valve selected, each of said valves having a part yieldable under pressure of the lever in the operation of the valve, and means for holding the lever in an operative position depressing a valve part.
10. 2. A water softener valve mechanism as set forth in claim 1 wherein the last mentioned means is arranged to serve for holding the lever in a position operating none of the valves.
15. 3. In a water softener, the combination with a softener tank containing softening material, and means for supplying hard water to said tank and withdrawing soft water therefrom, of a plurality of valves spring-20 operated one way and manually the other way arranged for controlling the communication between the softener tank and the source of hard water supply for softening and regeneration and to establish communica-25 tion between the tank and a drain outlet during regeneration, and a single lever for operating all of said valves, said lever being movable selectively to whichever valve it is desired to operate and when moved to such position being arranged to operate the valve selected against the action of its spring.
4. In a water softener, the combination with a water softener tank containing softening material, and means for supplying hard water to the tank and withdrawing soft water therefrom, of two valves controlling the communication between the source of hard water supply and the upper and lower 35 ends of the tank as required in the softening and regenerating operations, both of said valves having spring-operated plungers so that either is arranged to be operated only when the plunger is depressed whereby to have one valve open and the other closed, a single member for operating said valves movable selectively to a position over the plunger of either valve to operate the same by depression thereof, and means for holding said 40 lever in position holding either valve plunger depressed.
5. In a water softener valve mechanism as set forth in claim 4 the provision of means for varying the extent of opening of the 45 valves.
6. In a water softener valve mechanism as set forth in claim 4 wherein the valve operating member comprises a lever pivoted to be swingable to and from the valves, the 50 provision of means for adjusting the pivot for the lever whereby to vary the amount of depression of the valve plungers.
7. In a water softener valve mechanism as set forth in claim 4 the provision of a third 55 valve also of the spring-operated type hav-60 ing a part for manually operating the same disposed in the path of the valve operating member in the movement of the latter to one of the two other valves whereby the third valve is arranged to be operated in the operation of the other valve.
8. In a water softener valve mechanism as set forth in claim 4 the provision of a third valve also of the spring closed type having a part for operating the same disposed in the path of the valve operating member in the movement of the latter to one of the two other valves whereby the third valve is arranged to be operated in the operation of the other valve, the third valve 75 being arranged to be operated to a mid-position before the operation of the other valve commences and the lever being arranged to be held in an intermediate position holding the third valve in the mid-position.
9. In a water softener valve mechanism as set forth in claim 4 the provision of a third valve also of the spring closed type having a part for operating the same disposed in the path of the valve operating member in the movement of the latter to one of the two other valves whereby the third valve is arranged to be operated in the operation of the other valve, the third valve 80 being arranged to be operated to a mid-position before the operation of the other valve commences and the lever being arranged to be held in an intermediate position holding the third valve in the mid-position.
10. In a water softener, the combination with a softener tank containing softening material, and means for supplying hard water to the tank and withdrawing soft water therefrom, of two valves, one for controlling communication between the source of hard water supply and one end of the tank for softening operation, and the other 10 for controlling communication between the source of hard water supply and the other end of the tank for regeneration, a hand lever pivotally mounted to be swung to either valve to operate the same, said valves having spring means normally closing the same against which spring means the lever is forced to act, and means for holding said lever in position holding either valve open against its spring means.
11. In a water softener valve mechanism as set forth in claim 10 the provision of a third valve controlling communication between the tank and a drain outlet, said valve having a part for operating the same arranged for engagement by said hand lever whereby the third valve may be operated independently of the other two valves, said valve being normally closed under spring pressure against which spring pressure the 11

lever is arranged to act in opening the same, and means for holding said lever in position holding the third valve open.

12. In a water softener valve mechanism as set forth in claim 10, the provision of a third valve of the spring-closed type having a part for operating the same arranged for engagement by the hand lever whereby the third valve may be opened independently of the other two valves, the third valve in another position of the lever being also arranged to be held open when one of the other two valves is held open, and means for holding said lever in either of the two positions.

13. In a water softener, the combination with a softener tank containing softening material, and means for supplying hard water to said tank and withdrawing soft water therefrom, of a valve controlling communication for one end of said tank with the hard water supply, a hand lever swingable toward the valve to operate the same, and another valve controlling communication between the tank and a drain outlet and having a part also arranged for operation by said hand lever, the two valves being so related that one may be operated alone independently of the other or both may be operated jointly.

14. In a water softener, the combination with a water softener tank containing softening material, and means for supplying hard water to the tank and withdrawing soft water therefrom, of two valves controlling communication between the source of hard water supply and the upper and lower ends of the tank for softening and regeneration, both of said valves having spring means normally closing the same, a hand lever pivotally mounted between the two valves to be swung to either valve to open the same against the spring action, and a face plate in relation to which said lever is movable, having means for holding said lever in position holding either of said valves open.

15. In a water softener valve mechanism as set forth in claim 14 the provision of means for adjusting the fulcrum point of the hand lever in relation to the means on the face plate for holding the lever in different positions whereby to vary the amount of valve opening.

16. In a water softener valve mechanism as set forth in claim 14, the provision of a third valve also of the spring-closed type having an opening lever extending across the path of movement of the hand lever to be engaged and operated thereby in the movement of the latter toward one of the two other valves, said third valve being arranged to be operated independently of the other two valves, and the face plate having

means thereon for holding the lever in position holding said third valve open.

17. In a water softener valve mechanism as set forth in claim 14, the provision of a third valve also of the spring-closed type having an opening lever extending across the path of movement of the hand lever to be engaged and operated thereby in the movement of the latter toward one of the two other valves, said third valve being arranged to be operated independently of the other two valves, and the face plate having means thereon for holding the lever in position holding said third valve open, the third valve when operated alone being held open only part way with the lever in an intermediate position and being arranged to be opened entirely when the lever is moved farther to open the other valve, and the provision of means for adjusting the fulcrum point for said lever in relation to the means on the face plate for holding the lever in its different positions whereby to vary the extent of valve opening.

18. In a water softener, the combination with a softener tank containing softening material, and means for supplying hard water to said tank and withdrawing soft water, of valve mechanism for controlling the direction of flow of the water through said tank for softening and regeneration and arranged to establish communication between the tank and a drain outlet during regeneration, said valve mechanism being operable against spring action, a hand lever pivoted for movement from one limit position to another limit position and arranged to operate the valve mechanism differently in different positions to establish the proper connections for the tank for softening, regeneration, etc., and a face plate with relation to which the hand lever is arranged for movement, the face plate being provided with suitable markings to designate the different positions of the lever for the proper control of the softener, said plate having a guide slot provided therein, means on the face plate alongside the guide slot at the different marked positions, and a pin-selectively engageable with said means to extend across the guide slot at any one of the marked positions to hold the hand lever.

19. In a water softener valve mechanism as set forth in claim 18, the provision of an adjustable fulcrum for the lever adjustable in relation to the means on the face plate for holding the lever in its different positions whereby to vary the amount of valve opening in the different positions of the hand lever.

In witness of the foregoing I affix my signature.

LEE G. DANIELS.
